UNITED STATES PATENT OFFICE

167,175

DOLL OR THE LIKE

Milo Ryan, Seattle, Wash.

Application December 26, 1950, Serial No. 13,588

Term of patent 3½ years

(Cl. D34—2)

To all whom it may concern:

Be it known that I, Milo Ryan, a citizen of the United States of America, residing at Seattle, in the county of King and State of Washington, have invented a new, original, and ornamental Design for a Doll or the like, of which the following is a specification, reference being had to the accompanying drawings, forming a part thereof, in which:

Fig. 2 is a rear elevational view thereof; and

Fig. 3 is a side elevational view thereof.

I claim:

The ornamental design for a doll or the like, as shown.

MILO RYAN.
